SPRAYING APPARATUS

Francis W. Guibert, Los Angeles, Calif.

Application April 13, 1937, Serial No. 136,632

1 Claim. (Cl. 91—8)

This invention relates to an apparatus for spraying decorative materials onto a surface to which the materials adhere. Such decorative materials may be small flakes of mica, or other mineral matter, such as color, silica, or the like. The surface may be formed by a fresh coat, as of paint or other sticky material. The decorative pieces thus adhere to and become at least partially embedded in the paint.

Attempts to spray such decorative material have not heretofore been entirely successful. This is due to packing or arching of the material adjacent the outlet nozzle; and this is especially aggravated when light materials, such as mica flakes, are used.

It is one of the objects of this invention to obviate this disadvantage; and more particularly by providing an agitator for the material near the outlet.

It is another object of the invention to provide a simple and effective apparatus to effect the spraying of materials onto a surface.

It is still another object of the invention to utilize air pressure for the spraying as well as for the operation of the agitator.

It is still another object of the invention to make it possible to regulate or control the action of the air pressure for the spraying action as well as for the operation of the agitator, whereby the velocity and volume of the spray may be independently determined.

This invention possesses many other advantages, and has other objects which may be made more easily apparent from a consideration of one embodiment of the invention. For this purpose there is shown a form in the drawing accompanying and forming part of the present specification. This form will now be described in detail, illustrating the general principles of the invention; but it is to be understood that this detailed description is not to be taken in a limiting sense, since the scope of this invention is best defined by the appended claim.

Referring to the drawing:

Figure 1 is a longitudinal section of an apparatus embodying the invention;

Fig. 2 is a top plan view thereof, the cover being partly broken away;

Fig. 3 is a sectional view taken along plane 3—3 of Fig. 1; and

Fig. 4 is a fragmentary front elevation of the device shown in Fig. 1.

In the present form of the invention, the device incorporates a container 1 of sheet metal, shown in this instance as cylindrical. This con-

tainer may be arranged to have a cover 2 hinged at the top as at 3 so as to permit loading the container 1 with the flakes 4 of mica, or other decorative material which it is intended to spray onto a sticky surface. For ready manipulation the container 1 may be provided with a handle structure 5. This handle structure may be fastened to the container 1 as by the aid of the brackets 6 and 7.

In order to permit suspending the device from any appropriate support, a hook member 8 may be provided. This hook member can be appropriately supported as by the aid of the rivets 9 to the front upper edge of the container 1.

At the lower front portion of the container 1, a discharge nozzle structure 10 is provided. As shown most clearly in Fig. 4, this nozzle structure has a discharge opening of generally flat rectangular form. The nozzle 10 diverges toward the body 1 and communicates with the lower portion of the container 1 through an aperture 11. The bottom of the container 1 is conveniently formed by a sloping wall 12 having a bottom portion 13 immediately adjacent the opening 11. In this way the material 4 gravitates toward the bottom of the container 1 and toward the opening 11, which forms the entrance to the nozzle structure 10.

In the present instance, an air blast is used for ejecting the material 4 through the nozzle 10, after said material enters this nozzle through the aperture 11.

For this purpose, an air nozzle 14 is provided and arranged below the sloping wall 12. It has a discharge opening 15 which extends partially into nozzle 10.

Any convenient source of compressed air can be used to supply air pressure through the nozzle 14. The air connection is provided for example through a hose 16 coupled as by coupling 17 to a main control rotary valve 18. The valve 18 can be of the plug type, controlled as by handle 19. Its outlet 20 can project into the bottom of the body 1 and below the wall 12. In order to hold the valve 18 in proper position, a bracket 21 may be utilized extending from the side of container 1 to the cylindrical valve body 18. A further brace 22 may be provided between the inlet portion 23 of the valve to the handle bracket 19.

Within the container 1, and below the wall 12 thereof, the air connection is provided with a branch 24, controlled by a valve 25. This branch or by-pass has an outlet 26 projecting into the nozzle 14 at the aperture 27. The nozzle 14 is furthermore provided with a deflector 28 ad-

ja⁵cent the outlet opening 15 so as to cause a spreading of the air at the base of the nozzle 10.

Light flaky material, such as ground or flaked mica, has a tendency to pack or arch adjacent to the opening 11. The result is that little or no mica will pass through the nozzle 10. In order to prevent the occurrence of packing or bridging, a mechanical agitator 29 is provided within the container 1 and adjacent to the nozzle opening 11. This agitator may be in the form of a helical device, or a flat bar, which may be rotated by any appropriate source of power. For example, it is shown in this instance as a flat bar joined to a stub shaft 30, which may be detachably coupled to a shaft 31 of an air motor 32. The agitator 29 may project from below the bottom 12 through an aperture 33 at the base of the bottom 12.

Air motor 32 may be of any appropriate type, such as the turbine type. It is shown as having its inlet side in communication with the air supply, as at 34. It is provided with an exhaust connection 35 that also discharges through the nozzle 14, supplementing the air blast provided by the by-pass 26. The velocity of motor 32 may be controlled independently by a control valve 36. The motor structure 32 with the associated attached nozzle 14 may be supported as from a transverse brace 37. This transverse brace is fastened to the inside of the container 1 below the bottom 12. An angle iron 38, fastened to brace 37, has a leg attached to a flange 39 of the motor 32 for supporting it.

The supply of air to nozzle 14 for ejecting the material 4 through the main nozzle 10, is provided both from the exhaust of the motor 32, as well as from the by-pass connection 26. The total volume of air through the nozzle 14 is controlled by valves 25 and 36, which independently control respectively, the flow of air through the by-pass 26, and the flow of air through motor 32 to control its velocity.

Furthermore, the inlet aperture for the nozzle 10 may be controlled by a slide or gate 40, guided by the flanged guide strips 41 (Fig. 4), and ma-

nipulatable from the exterior of the container 1. The lower edge 42 of the gate 40 overlaps the opening 11.

By the aid of the controls provided, it is possible to provide a slow ejection of the material 4 or a fast ejection of material 4. Furthermore, by proper manipulation of valves 18, 25 and 36, the speed of motor 32 may be varied and therefore of the agitator 29; and this is accomplished independently of the total amount of air passing to the base of nozzle 11.

The manner of use of the device may now be summarized. The light material 4, which may have a tendency to pack, is loaded into the container 1. The gate 40 is moved to the proper position to determine the quantity of flow of the sprayed material. The velocity of agitator 29 is controlled by valve 36. The total amount of air passing to the base of nozzle 10 may be adjusted by the aid of the valve 25, which controls the amount of air supplementing that derived from the exhaust 35 of motor 32.

What is claimed is:

In a device for spraying light divided material that is liable to pack or arch, said device being arranged to be entirely supported as well as manipulated, by one hand, a shell, a sloping partition in the shell whereby the upper part of the shell forms a container for said material, means forming a discharge nozzle for the container, there being an opening at the bottom of the container whereby material may pass freely and directly from the container into the nozzle, a mechanical agitator within the container immediately adjacent the opening, a motor supported within the shell outside the container for operating the agitator, and an ejector nozzle without the container adjacent the partition and having its orifice immediately adjacent said opening, whereby pressure fluid discharged by the ejector nozzle will be effective to draw material into the discharge nozzle from the container and discharge it from the nozzle.
